GAS AND LIQUID PUMPING AND SEPARATING APPARATUS

Porter S. Morgan, Westport, Conn., assignor to
American Brake Shoe Company, a corporation
of Delaware

Application August 8, 1942, Serial No. 454,126

12 Claims. (Cl. 103—6)

This invention relates to pumping apparatus of a type particularly applicable to service in vacuum heating systems, or to other duty wherein it is desired to supply a main pump, such as a centrifugal, with air-free liquid. It is directly concerned with pumping apparatus embodying an auxiliary or primer pump, by means of which suitable suction may be maintained at the inlet of the main liquid pump, with the concurrent elimination of air which would tend to destroy the suction and interfere with the liquid pump operation.

Heretofore in the art of self-priming centrifugals, it has been proposed to provide an auxiliary pump, in the form of a jet or ejector, rotary pump, or the like, connected to the centrifugal in such manner that the liquid to be pumped thereby is freed from entrained air. Such self-priming centrifugals have been proposed for use in vacuum heating systems, wherein considerable quantities of air are included in the water. In such systems, the idea is to pull the steam through the radiators by applying a vacuum on the condensing end, rather than pushing the steam through by high pressure generated at the boiler, this for reasons of economics and safety. The circuit therefore invariably comprises the boiler, the radiators and connecting piping, check valves leading from the radiators to the return manifold, and the pumping equipment connected to the return line in such manner as to withdraw the returns, composed of the condensed steam and admixed air, shake out the air, and deliver the water again to the boiler. This is a well-known system, referred to here as illustrative of the uses of the present invention, without, however, intending to suggest that the invention may not be applied to various other duties.

In the development of this art over the past thirty years, considerable attention has been given to the design and characteristics of the vacuum-creating, or priming pump member. Since there is no advantage in delivering air to the boiler, elimination of all incondensable returns is indicated. Moreover, centrifugal pumps "lose their prime" when the inlet is clogged with air, the centrifugal will create a suction when acting on water alone, but will fail to maintain that suction if there is enough entrained air to form globules in the eye or the vanes of the impeller. Since the relative volumes of air and water are variable, depending upon the extent of leaks and the number of radiators in the circuit at any time, the duty of handling both air and water is thrust upon the primer or auxiliary

5 pump. This is a severe task, as a good water pump may not be a good air pump, and vice versa. For these, and other reasons, it may be surmised that the heart of the system is in the primer, and if it is inefficient, the system is also.

10 Of the numerous types of primers which have been devised, the jet and various forms of rotary pumps appear to have survived in commercial practice, although they are not perfect as a matter of pure engineering. In general, the jet is rather inefficient and has a limited capacity, while the commercial forms of movable-parts primers are relatively expensive, and are otherwise objectionable. In the present invention, 15 this phase of the system, whether applied to vacuum heating or other duty, is improved upon by providing a priming pump, having few moving parts and of simple construction, and which operates effectively with both large and small volumes of returns, and with wide variations of the liquid-air ratio in such returns.

20 In one aspect, the present invention is embodied in a primer pump or air separator adapted to be associated with the main liquid pump, comprising a substantial number of chambers 25 adapted to contain water or other liquid, and which are successively connected to the return line, as the water in each is withdrawn, to create a vacuum. Those chambers which are not so connected to the return line are either dormant at the moment, or are being flooded with water to expel such air as may be therein, so that, when 30 they in turn are connected to the return, the withdrawal of the water will continue to apply the vacuum or reduced pressure. The selection of the several chambers for inducting the returns, assuming an idle status, or preparing for service, is effected by means of positively operated 35 valves governing the events occurring in each of the chambers.

35 The water volumes which enter or drain from the chambers thus become liquid pistons, operating either to expel air, or to induce a flow of air and water. 40 Because of the nature of the pistons, they need no packing or other attention, and the pump of which they form an operative part is effective on air, and water, or the two combined in any proportion. The water forming the pistons of all the chambers is fed to and may be supplied by the main pump, and any excess is supplied by the main pump to the boiler, or other delivery point, by discharge past a check valve. 45 Other aspects of the invention will appear more readily from a perusal of the following descrip- 50

tion of a preferred embodiment, illustrated in the accompanying drawings, wherein:

Fig. 1 is a side view of a combined centrifugal pump, primer pump, and motor assembly, with the primer pump elements being shown in section;

Fig. 2 is a top plan view of the assembly, the upper cover plate of the primer being removed;

Fig. 3 is a view partially in elevation and partially in section, looking toward the primer component as indicated by the line 3—3 of Fig. 1;

Figs. 4 and 5 are enlarged fragmentary views taken on the lines 4—4 and 5—5 respectively of Fig. 1, showing the upper and lower port and valve relationships;

Fig. 6 is a schematic view to illustrate the cycle of action within the several chambers of the primer, the chambers being here laid out in line rather than radially as in the previous figures; and

Fig. 7 is a section taken on the line 7—7 of Fig. 2, illustrating the construction of a check valve.

Referring first to Figs. 1, 2, and 3, there will be seen a frame 10 having mounted thereon a motor 11 connected at one end to a centrifugal pump 12 and at the opposite end to a speed reduction gear box 13. A cylindrical tank assembly, generally designated by the numeral 14, is mounted on the frame 10 above the speed reducer, and certain parts contained in the tank are driven by the motor 11 through the reducer 13 by means of a countershaft 15. The tank assembly 14 composes the primer pump and air separating constituents of the apparatus, while the centrifugal 12 is employed as the main liquid pump.

The upper end of the assembly 14 is provided with a fitting to receive a pipe 16 which is coupled to the return line of the vacuum heating system, the suction line of the well, or other point from which fluid is to be withdrawn. The lower end of the assembly 14 is provided with a cored fitting 17 having two spaced lateral taps 18 and 19 through which liquid may flow from or to the tank. The tap 18 is connected by piping 21 to the inlet or eye 22 of the centrifugal pump 12, while the discharge opening 23 of the centrifugal is coupled to a T 24 which leads both to and away from the tank 14. One branch of the T is coupled to the tap 19 through piping 25 and a shut-off valve 26, while the opposite branch is coupled to piping 27, including a check valve not shown, which leads to the boiler or other delivery point.

The circuit just outlined is such, therefore, that whatever there is to be pumped enters the tank assembly 14 through the inlet fitting 16, and here any entrained air is separated, as will be described more fully directly. Water in the tank 14 flows to the centrifugal pump 12 through the outlet opening 18, and from the pump 12 the water may flow either to the tank 14, or to the main delivery point, or both, depending on the quantity and how the valves are set. Liquid returned to the tank assembly 14 is essentially intended to create the water pistons heretofore mentioned, while any excess thereover, coming in through the pipe 16, is the liquid to be pumped to some extraneous point.

The tank assembly 14 comprises a lower cylindrical member 31, which, as best shown in Fig. 2, is radially divided into six chambers 32 by webs 33. These webs converge at the center into a tube 34 which is conically flared at both upper and lower ends, as indicated by the numerals 35

and 36 respectively. The lower portion of the member 31 is formed with a conical bottom 37 which merges into the flared wall 36, except for spaced apical openings 38 each providing an entrance into its associated chamber 32. These openings 38 each communicate with a duct 39, formed between the lower portion of the tube 34 and the bottom 37. The lower portion of the tube 34, as it will be noticed from Figs. 1 and 3, is provided with a second flared section 41, generally concentric with the tapered bottom 37, and the ducts 39 are formed by suitable coring. Each duct 39 is brought down toward the apex by the formation of the wall 41. The bottom wall 37, at this region, is cut away and is finish ground to provide a conical seating portion 42, and a pad 43 which supports the fitting 17. The sections of the ducts 39 adjacent the seating portion 42 constitute port openings, regularly spaced in a circumferential direction, and sweeping out sixty degrees of arc less whatever is required for the walls of the ducts. Through these, liquid may enter or leave the chambers 32, depending upon conditions.

The upper flared wall 35 does not merge into the side wall of the cylinder 31, but is stopped off as an annulus 45, whose margin is finished to provide a pad, and whose upper wall is also finished to form a conical seat 46. The wall 35 is also formed with six openings 47, one for each chamber 32, regularly spaced around the circumference and in alignment with the port openings of the ducts 39. These are also shown in Fig. 4. Liquid and air may enter the chambers 32 through the openings 47, but they differ functionally from the openings in the ducts 39, in that reverse flow through the openings 47 need not occur.

A second substantially cylindrical tank 51 is mounted on top of the cylinder 31, resting on the pad of the annulus 45 and an internal flange 52 on the wall of the tank 31. The tank 51 is formed with a bottom wall 53, covering the openings 54 of the chambers 32, and provided with a raised central portion 55 which is formed with a pair of radial seats 56 and 57 and a cap section 58. Referring primarily to Figs. 2 and 3, it will be seen that the central portion 55 communicates with a cored duct 59 which extends radially to the outer wall of the cylinder to provide the fitting for the inlet pipe 16. Thus, the returns entering the apparatus through the pipe 16 flow through the central portion 55 for distribution to the various port openings 47 for the chambers 32, while in somewhat similar manner the lower portions of the chambers 32 are placed in communication with the liquid pump 12 through the fitting 17.

With this description of the chambers and their ports and manifolds, reference will now be made to the valve arrangements whereby they are brought into play. It will be noted that the countershaft 15, which is driven by the motor 11 at a relatively low speed, extends up through the fitting 17 and above the central portion 55, passing through the tube 34. This shaft carries at each end a rotary valve whose positions determine the instantaneous condition of the chambers 32. The lower valve 61 (see also Fig. 5) comprises a conical surface 62 having an upper cylindrical extension 63 which is pinned and keyed to the shaft 15 prior to final assembly of the apparatus. The valve 61 also has a short depending cylindrical skirt 64 and a long skirt 65, whose outer walls are concentric with the shaft 15. These skirts respectively bear in aper-

tures formed on the upper side of the fitting 17, and an internal dividing wall 66 which separates the openings 18 and 19 from each other.

The conical surface 62 is cut away or is formed to provide two valve openings 67 and 68, each subtending substantially 120° and spaced from each other by arcs of substantially 60°. One opening communicates with the space within the skirt 65, while the other opening communicates with the space between the skirt 65 and the skirt 64, and therefore each valve opening 67 or 68 provides communication with the opening 19 or the opening 18. As shown in Fig. 5, and also in Fig. 1, the arrangement here is such that valve opening 67 is in communication with the liquid line 25, while the opening 68 is in communication with the line 21.

The conical surface 62, when in assembled position, bears on the ground surface 42 of the lower wall 37. As the openings 39 in this wall are spaced sixty degrees, and since the openings 67 and 68 sweep out twice that arc, it will be apparent that, at any moment of rotation, each opening provides communication between two circumferentially adjacent chambers 32 and the connected pipe line 21 or 25, and each pair of such chambers is spaced from the other pair by one interjacent chamber 32 which, at the moment, is idle. As the valve rotates, the status of these chambers changes accordingly.

The upper valve member 71 is generally similar to the lower valve 61, except that it has only one port, instead of two, and therefore so much of the description as is common need not be repeated. As a practical matter, the upper and lower valves are initially made alike, if they are cast with cored openings, then the one port for the upper valve is closed by a plug 72, shown in Fig. 1. Or, if the ports are cut out later, then only one need be made in the upper valve. The conical surfaces and bearing portions of the upper valve 71 seat on the surfaces 46, 56, and 57 in a manner comparable to that just described. In Fig. 4, there is shown in plan the upper conical surface 46 with the inlet openings 47, and it will be understood that, except for the difference in ports, the views of Figs. 4 and 5 may be regarded as separate views of the mating surfaces of both valve assemblies.

In assembling the valve structure, the lower valve 61 is first located on the shaft 15, and then in the fitting 17, and the shaft, valve, and fitting are inserted up through the bottom of the tank 31. The upper valve 71 is then positioned on the shaft 15, and is keyed thereto, but not pinned. Then the upper cylinder 51 is dropped into place, and a collar 74 located over the shaft end around the valve extremity and the surface of the upper portion 52. A coiled spring 75 and securing nut 76 are then added and adjusted so as to hold the valves in position with a minimum of friction or leakage losses.

The unplugged opening of the upper valve 71 is aligned with the opening 63 of the lower valve, and thus the opening in the upper valve connects the return line 16 to that pair of chambers 32 which are connected to the pipe 21 leading to the inlet of the centrifugal pump 12.

Prior to positioning the upper chamber 51, a hollow ball 81 may be placed in each chamber 32. This ball is of such size as to seat in the opening 38 when the liquid level drops, and it thus functions as a safety device or valve to prevent total drainage of the liquid contents. The ball naturally finds its seat by rolling down

the conical walls 36 and 37, and when the liquid level rises, it floats around on the top of the water. Because the ball cannot interfere with anything, it need not be guided.

The bottom wall 53 of the upper tank 51 is provided with six uniformly spaced taps, each of which receives a check valve 82, shown in section in Fig. 7. These are located over the openings 54 of the chambers 32, and serve to permit air to escape therefrom. Each valve 82 consists of a threaded stem 83 having a bore 84 and a shoulder 85, the lower part of the stem being screwed into the wall 53, and the upper part receiving a cap 86. The cap, which encloses a ball 87 seating on the stem end to close the bore 84, is formed with two side openings 88 and a top opening 89. When air, or water, pushes up through the bore 84, the ball 87 is displaced to permit flow into the upper cylinder 51, but when there is no upward pressure, the ball seats by gravity, and thus closes the opening 84. The free passageway around the ball within the cap is adequate to permit rapid escape of air, but it offers increased resistance to the flow of water, and hence limits the amount of water which can enter the upper cylinder 51.

The upper cylinder 51 is provided with a float valve assembly for returning water to the chambers 32. For this purpose, the bottom wall 53 is formed with a boss 91 which has a cored duct 92 leading to the inlet duct 59 (see Fig. 2). A valve unit 93 is mounted on top of the boss 91, and it is made up of a slotted post 94, to which a lever arm 95 is pivoted. The arm carries a float ball 96, and thus lifts and lowers in response to the liquid level in the cylinder 51. A stem 97, having a valve 98 at its lower end, is carried by the lever 95, and is guided in the post 94 to abut a valve port 99 which communicates with the duct 92. Thus, when the float ball is lifted, water may drain from the upper cylinder back into the inlet line 59 for return to the chambers 32, and when the ball drops, the pathway is closed.

The cylinder 51 is covered by a plate 101 formed with a boss 102 which is located in alignment with the boss 91. A valve body 103 is positioned in the boss 102 to encircle the upper end of the stem 97 and a second valve element 104. When the float arm 95 is down, the valve 104 is removed from its seat in the body 103, and hence air entering the upper cylinder may flow freely to atmosphere. As the float arm raises to open the valve 98, the upper valve 104 approaches its seat, and closes against it shortly after the lower valve has opened. This precludes the escape of water to the atmosphere, and tends to build up a pressure within the cylinder 51 aiding the rapid drainage of the water back into the chambers 32.

In order to simplify an explanation of the operation, reference will be made to Fig. 6, in which the system is shown somewhat schematically, and like reference numerals have been employed for the functional parts corresponding to those just described. The six chambers 32 of the tank assembly 14 are shown in line, and each has been given an identifying reference character, such as 32a, 32b, etc. Only the lower valve 61 is shown, and its two ports have been so located that drainage port 63 spans chambers b and c, while the flooding port 67 spans chambers e and f. Clockwise rotation will be assumed.

Recalling that the valve 61 is positively driven by the motor 11 at a low speed compared to the speed of the centrifugal pump 12, it will be seen

that, at the instant depicted, chambers *b* and *c* are connected through port *68* and pipe line *21* to the inlet of the centrifugal, and hence the liquid entering the centrifugal flows in from these chambers. At the same instant, due to the alignment of the single port in the upper valve *71* with the port *68*, these same chambers are also connected to the return line *16*. Hence, as long as these chambers are so ported, whatever there is in the return line *16* may flow through chambers *b* and *c* to the liquid pump.

The returns consist, in all probability, of a mixture of water and air, and, as the chambers *32* are of appreciable size, the air separates from the water and occupies the clear space above it. At this same instant, the discharge side of the centrifugal pump *12* is connected, through the branch *25* and the port *67*, to chambers *e* and *f*, and thus some of the discharge water will flow into these chambers, flooding them, and expelling contained air through the appropriate ball check valves *82*. Excess water flows through the branch *27* to the delivery point.

A few moments later, however, due to the rotation of the valves *61* and *71*, chambers *c* and *d* will be connected to the drain port *68*, while chambers *f* and *a* will be connected to the flooding port *67*. As the valve continues to rotate, one chamber of each pair will thus go out of service to be replaced by the next in line, and hence the several chambers are successively called into play to serve as supply chambers, or receivers, for the liquid.

At the instant illustrated, therefore, chamber *a* is dormant, having just gone out of service as a supply chamber, and accordingly its liquid volume is low. Chamber *d*, which previously had been open to the discharge of the liquid pump, is flooded and also dormant except as the supernatant air may continue to escape. The other chambers contain intermediate quantities of liquid, depending on the length of time they have been connected to the valve ports. The action thus continues around the circle of chambers, with the water acting as pistons, creating suction on the line *16* when it drains, and forcing out the previously separated air when it enters. Because of the porting arrangement, each chamber, when draining, can contribute to three other chambers located at least one intervening chamber away.

The valve *26*, located in the line *25* through which water is returned to the chambers *32*, should be adjusted as conditions change, so that no more water enters the receiving chambers than is required to provide the pistons. The reason for this will be apparent upon considering the variations occurring in the air and water ratio in the returns. If only air is being returned, then there is no excess of water to be delivered to the delivery branch *21*, and everything draining from chambers *b* and *c* is needed to supply the water pistons for chambers *e* and *f*. This is one extreme condition, and at this time the valve *26* should be opened, so that all the water can flow where it will do the most good.

If only water is being returned, it will flood chambers *b* and *c* as fast as they drain, since the upper inlet port and lower drain ports are in line. Hence, when chambers *b* and *c* take the *e* and *f*, or flooding positions, they need no water, and at this time the valve *26* may as well be closed, so that the water cannot accumulate, but is diverted through the branch *21*.

The more usual condition is, however, a mixture of air and water, so that chambers *b* and *c* do

not drain completely, but retain whatever fraction of their total volume may be supplied by the return water. When they are in turn opened to the line *25*, they therefore need only a percentage of their volume to make up the water pistons, for otherwise they would tend to be overcharged with water which would be expelled through the valves *82* without doing any useful work. Accordingly, at this time, the valve *26* should be partially closed so as to throttle the line and limit the supply.

The valve *26* has been shown as a hand valve, and it will be apparent that full automatic operation would indicate a modulating valve, self-adjusting against changes in the air and water ratio. Such a valve, per se, forms no part of the present subject matter, however, nor is it essential to operation, and therefore further discussion of this point will not be made.

It will be seen that the group of chambers, operating with water as described, constitutes a multiplex positive displacement reciprocatory pump whose mechanical wearing parts consist solely of the two valves *61* and *71*. Since the bearing surfaces are constantly flooded with water, and minor leakage losses over the surfaces do not interfere with operation, it is apparent that such apparatus has a long life and will require but little attention. Moreover, due to the multiplicity of cylinders or chambers *32*, and the fundamental nature of the action, the pump runs with practically no pulse, thus bringing its characteristic in this respect into harmony with the characteristic of the centrifugal pump *12*. The large number of chambers moreover provide a high volumetric space for the separation of air, and accordingly the unit, considered as an air separator, has a high capacity. It should also be remembered that the unit, considered as a pump, will operate effectively on air, or water, or both, in any ratio, and with varying total quantities.

Those skilled in the art will appreciate that the present invention provides a relatively inexpensive and effective way in which to separate mixtures of air and water with concurrent delivery of the water to a main liquid pump, and that the invention may be utilized to advantage in numerous applications. It will also be understood that while the invention has been described with reference to one specific embodiment thereof, it is not limited thereto, but is susceptible of numerous modifications and rearrangements, all of which are intended to be encompassed by the scope of the following claims.

I claim:

1. A gas and liquid pumping and separating apparatus comprising a plurality of chambers each having an inlet for a mixture of gas and liquid, means for connecting each of such chambers in turn to the mixture to charge each chamber therewith, duct means for each chamber through which liquid entering from the inlet may be withdrawn and through which gas-free liquid may be supplied to each chamber, movable valve means for successively opening and closing the duct means whereby each chamber may be drained and may thereafter be flooded with liquid entering through said duct means, said inlet connecting means and said movable valve means operating in timed relationship whereby a chamber being flooded is disconnected from said inlet, a relief port for each chamber through which gas and adventitious liquid may escape during the flooding of the chamber, and means for recovering such adventitious liquid.

titious liquid and directing it back into the mixture.

2. A gas and liquid pumping and separating apparatus comprising a plurality of chambers positioned in circular fashion alongside of each other, duct means at the bottom of the chambers through which gas-free liquid may enter to flood the chambers and gas-free liquid may also drain from the chambers, other inlet means at the top of the chambers through which mixed gas and liquid may enter the chambers and separated gas may leave the chambers, rotary valve means for controlling the opening and closing of the ducts and inlets through which liquid may enter and leave the chambers, said valve means being formed with ports fixedly related to each other whereby, when any chamber is connected to a source of mixed gas and liquid, the same chamber is closed to the entrance of gas-free flooding liquid, and another of said chambers is open to the flooding liquid and closed to the mixed liquid, said named chambers being spaced by an intervening chamber closed to both mixed and flooding liquid, and means for progressively changing the positions of the ports with respect to the chambers in successive order, whereby one chamber drains to create a suction, another floods to create pressure, and the intervening chamber is given a dormant period to assure the expulsion of gas therein by the pressure theretofore created.

3. In a gas and liquid pumping and separating apparatus, a plurality of chambers each of which is provided with an inlet for a mixture of gas and liquid, and duct means for draining liquid and flooding the chambers with gas-free liquid, valve means for said inlets and ducts successively connecting each chamber to the mixture while connecting the chamber for drainage and simultaneously connecting another chamber for flooding, whereby alternate flooding and drainage of the chambers is effected with creation of suction during draining and creation of pressure during the flooding phase, vents in each chamber through which gas may escape during such flooding phase, a recovery vessel in communication with all of said chambers through said vents into which such gas and any adventitious liquid may escape, means in the recovery vessel for discharging the gas entering thereinto, and other means in the recovery vessel for returning the liquid therein to the inlet for the mixture of gas and liquid and to the chamber then connected thereto.

4. In a gas and liquid pumping and separating apparatus, a plurality of chambers provided with openings and ducts and valves therefor whereby each chamber may periodically receive flooding liquid acting as a piston to expel air therein, may discharge such liquid to drainage to create a suction piston, and may induce a charge of mixed gas and liquid during drainage to the chamber, a recovery vessel superimposed on all of the chambers, a vent in each chamber through which the air therein flows to the recovery vessel, an inlet line in the vessel through which mixed liquid is supplied to said chambers, a float valve in the vessel opening in response to accumulations of liquid entering the vessel with the air, a passageway from the float valve to the inlet line whereby accumulated liquid is recovered to the chambers, another air vent in the vessel through which the air entering therein may be discharged from the apparatus, and means in the last named air vent preventing the discharge of the accumulated liquid from the apparatus.

5. A gas and liquid pumping and separating apparatus comprising a substantially cylindrical member divided into a plurality of chambers having ducts formed at the bottom thereof, a valve member positioned at the bottom of the member having spaced ports adapted to be aligned with certain of the ducts and spaced from other ducts at any moment of operation, a shaft connected to the valve member, means for rotating the valve to open and close the ducts successively, a fitting positioned adjacent the valve member and formed with two passageways, means connecting one passageway with one port of the valve member and the other passageway with another port, and a liquid pump having an inlet connected to one passageway and an outlet connected to the other passageway whereby the pump may receive liquid from successive chambers and deliver liquid to other successive chambers as the valve shaft is rotated.

6. A gas and liquid pumping and separating apparatus comprising a cylinder internally divided by radiating webs into a plurality of chambers, a central tube formed at the junction of the webs extending through the cylinder, said webs and tube being angularly disposed at the ends of the cylinder to form surfaces of revolution, openings to each chamber formed in each surface, a valve member positioned on the surface at one end of the cylinder, said valve member having a port, means associated with the valve member to admit mixtures of gas and liquid through the port to the chamber whose opening is aligned therewith, a second valve member positioned on the other surface, said second valve member having two spaced ports adapted at any time to be aligned with the openings of two spaced chambers, and a shaft extending through the tube and connected to the valve members to operate said valve member in fixed relationship to each other.

7. A gas and liquid pumping and separating apparatus comprising a substantially cylindrical tank internally provided with radiating webs dividing the tank into a plurality of chambers, a central tube formed at the junction of the webs, openings and ducts formed at the ends of the tank and adjacent the tube, valve members positioned adjacent the tube ends and webs to cover said openings and ducts, one of said valves having a port through which liquid and gas may enter the chambers and the other of said valves having two port openings through which liquid can simultaneously drain from one chamber and enter another spaced chamber, a shaft extending through the tube and supporting said valve members, said shaft aligning the port opening of one valve with a port opening of the other valve, and means for rotating the shaft to advance the valves simultaneously to open and close the openings and ducts of the successive chambers.

8. In a gas and liquid pumping apparatus, a plurality of chambers adapted to receive a mixture of gas and liquid from an extraneous source, ducts for each of said chambers through which liquid entering the apparatus may be drained and gas-free liquid may be flooded into said chambers, valve means covering said ducts, said valve means including spaced ports, one of said ports constituting a drainage port and another of said ports constituting a flooding port, said valve means and ports being so disposed with respect to said ducts as to couple two chambers in parallel for drainage and two other chambers for flooding, and means for progressively changing

the registry of the ports and ducts whereby one of such chambers is isolated from the other but is replaced by still another chamber.

9. A gas and liquid pumping and separating apparatus comprising a substantially cylindrical tank internally provided with radiating web walls dividing the tank into a plurality of chambers, an opening formed in each chamber at one end and a duct formed in each chamber at the other end, said ducts and openings each sweeping out arcs less than that of the chamber, a rotary valve positioned at each end of the cylindrical tank to cover the openings at one end and the ducts at the other end, said valves being formed with ports each of which sweeps out an arc overlapping the openings and ports of two adjacent chambers, and means for rotating the valves whereby each chamber will be successively coupled in parallel to an adjacent chamber and will thereafter be isolated from the chamber to which it had just been coupled.

10. A gas and liquid pumping apparatus comprising a substantially cylindrical tank formed with radiating webs dividing the tank into six chambers, an opening at one end of each chamber and a duct at the other end of each chamber, a valve positioned to cover the openings and another valve positioned to cover the ducts, said first named valve having a port spanning the openings of two adjacent chambers, said other valve having two ports each spanning two adjacent chambers, one of the ports of the other valve being aligned with the port of the first named valve and the other port of the last named valve being spaced therefrom a chamber's arc, means for supplying mixed gas and liquid to the first named valve and means for supplying liquid to and removing liquid from the other valve, and means for rotating the valves in unison to align the ports thereof successively with the chambers.

11. A gas and liquid pumping apparatus comprising a substantially cylindrical tank internally provided with radiating webs to divide the tank into a plurality of chambers, an internal tube within the tank at the junction of the webs, said internal tube sloping toward the tank wall at the ends thereof, inlet openings formed in the sloping portion of the tube at one end thereof for each chamber, a valve member positioned over

said openings, said valve having a port adapted to be aligned with said openings successively, ducts formed in each chamber adjacent the sloping portion of the tube at the opposite end of the tank, a second valve member positioned over said ducts, said second valve member having spaced ports adapted to be aligned with the ducts of spaced chambers successively, means extending through the tube for connecting said valve members for simultaneous movement to bring the ports thereof into registry with the openings and ducts, skirt members on said second valve defining independent passages communicating with the spaced ports thereof, a divided fitting embracing the skirts, liquid communication lines connected to the divided fitting, means on one line to drain liquid from the chambers through one of said ports, and means on the other line to supply liquid through another port to other chambers simultaneously.

12. In a gas and liquid pumping and separating apparatus, a supply line adapted to contain a mixture of gas and liquid, a liquid pump for supplying gas-free liquid, a plurality of chambers each provided with an inlet opening, valve means for said openings, means interconnecting the valve means and the supply line to admit quantities of the mixture to the chambers successively, a duct for each chamber, a second valve means for the ducts, said second valve means having ports one of which is adapted to be registered with one chamber while another port is registered with another chamber, piping connected to the ports of the second valve means, said piping extending to the inlet and the discharge of said liquid pump whereby mixed gas and liquid admitted to the chambers may in turn be delivered to the inlet and liquid from the discharge may be directed to another chamber, an adjustable valve positioned in the discharge piping in advance of said port of said second valve whereby the quantity of liquid supplied by the liquid pump to the chambers may be regulated, and a branch line connected to the liquid pump discharge in advance of the adjustable valve whereby liquid discharged by the liquid pump in excess of the amount able to pass the adjustable valve is diverted from the apparatus.
